UNITED STATES PATENT OFFICE

156,282

DESIGN FOR A PORTABLE POWER-DRIVEN BAND SAW

William Paul Schepige, Newark, N. J.

Application August 14, 1948, Serial No. 148,122

Term of patent 7 years

(Cl. D93—3)

To all whom it may concern:

Be it known that I, William P. Schepige, a citizen of the United States of America and a resident of Newark, in the county of Essex and State of New Jersey, have invented a new, original, and ornamental Design for a Portable Power-Driven Band Saw, of which the following is a specification, reference being had to the accompanying drawing, forming a part thereof.

Figure 1 is a top plan view of a portable power-driven band saw, showing my new design;

Figure 2 is an elevational view of one side thereof;

Figure 3 is a bottom plan view of the portable power-driven band saw;

Figure 4 is an elevational view of the other side thereof;

Figures 5 and 6 are elevational views of the opposite ends of the portable power-driven band saw, respectively.

I claim:

The ornamental design for a portable power-driven band saw, as shown.

WILLIAM PAUL SCHEPICE.
